UNITED STATES PATENT OFFICE.

EBEN JOHN BEGGS, OF NEW YORK, N. Y.

APPARATUS FOR MANUFACTURING FININGS FROM FISH-SOUNDS AND ISINGLASS.

SPECIFICATION forming part of Letters Patent No. 372,591, dated November 1, 1887.

Application filed June 18, 1887. Serial No. 241,735. (No model.)

To all whom it may concern:

Be it known that I, EBEN JOHN BEGGS, a citizen of the United States, and a resident of New York, in the county of New York and State of New York, have invented certain new and useful Improvements in Apparatus for Manufacturing Finings from Fish-Sounds and Isinglass; and I do hereby declare that the following is a full, clear, and exact description 5 of the invention, which will enable others skilled in the art to which it appertains to make and use the same, reference being had to the accompanying drawings, which form a part of this specification, and in which—

15 Figure 1 is a perspective view of my improved device or apparatus for manufacturing finings from fish-sounds and isinglass. Fig. 2 is a transverse vertical sectional view of the same. Fig. 3 is a perspective view of one of 20 the sieves with the spindle, with its radiating-brushes mounted therein in operative position. Figs. 4 and 5 are perspective detail views of the coarse sieve and the fine sieve, respectively. Fig. 6 is a perspective detail 25 view of the spindle with its adjustable brushes; and Fig. 7 is a vertical sectional view of the lower portion of the device, the shaft and brush being shown in dotted lines.

30 The same letters of reference indicate corresponding parts in all the figures.

My invention consists in a new and improved device or apparatus for manufacturing finings from fish-sounds and isinglass; and my invention will be hereinafter fully described 35 and claimed.

Referring to the several parts by letter, A indicates the hopper of my improved device or apparatus, the side walls, A' A', of which converge somewhat toward their lower ends, 40 the lower end of the hopper proper being open, while about one-half of the distance from its top the hopper is formed with the partitions B B, which extend lengthwise of the hopper, with a suitable space, C, between their inner longitudinal edges, through which 45 space the fish-sound or isinglass feeds down in a suitable stream into the sieve below, the partitions B B sloping down toward their inner longitudinal edges.

50 D E indicate, respectively, the coarse and fine sieves, each of the said sieves being

formed with the parallel solid end pieces, F F, having the straight upper and curved or rounded lower edges, and the side pieces, G G, at the upper ends of the said end pieces, 55 the straight upper edge of each of the said end pieces being recessed longitudinally on its inner edge to form the flat longitudinal shoulder F', as shown, the wire-cloth H, which forms the curved bottom of each sieve, being tacked 60 or otherwise secured to the said end and side pieces, as shown.

The lower end of the hopper A has secured around it, at a little distance above its lower extremity, the ribs or flanges I I, which bear 65 against the upper edges of the end and side pieces of the sieves when the hopper is placed on the sieve, the lower ends of the hopper below these ribs extending down within the inside of the recessed upper ends of the end pieces, 70 F F, resting on the shoulders F' F' on the inner side of the said ends of the sieve, while the lower ends of the sides of the hopper below the side ribs or flanges, I, are beveled on their outer sides to fit within the sloping inner sides 75 of the side pieces of the sieve. By this construction a close joint is formed between the lower end of the hopper and the upper end of the sieve, which effectually prevents the escape 80 of anything from the hopper, except through the openings of the sieve-cloth. The sieve is secured to the lower end of the hopper by means of hooks J J on the lower ends of the hopper, which engage with eyes K K on the ends of the sieve, as shown.

85 One of the sieves is covered with coarse wire-cloth, while the other is covered with fine wire-cloth, for the purpose hereinafter specified.

90 Each of the sieves has formed in the inner side of one of its ends, extending down from the top of the said end through the shoulder F', as shown, a recess, L, which forms a bearing for one end of the removable spindle or shaft which carries the radial brushes, while 95 the other end piece of the sieve is formed with a vertical slot, M, extending down from the top or upper edge of the end piece for a short distance below the top or upper straight edge of the shoulder F', as shown, this slot forming 100 a bearing for the other end of the brush shaft or spindle, a metal bushing or bearing-plate,

N, being secured in the end slot and the end recess to prevent wear as the shaft or spindle revolves.

O indicates the brush shaft or spindle, which 5 is of the requisite length, and which is formed with the cranked end having a handle, P, at its outer end. Through this shaft O, toward each of its ends, extend the radial arms Q R, which are formed toward their outer ends with 10 the longitudinal slots S, through which pass the headed screw-bolts T, which secure the longitudinal brushes to the said radial arms. These longitudinal brushes U have the transverse apertures V formed through them to 15 ward each end, and through these apertures extend the screw-bolts T T, which are first passed through the slots S of the arms Q and R, then through the perforations of the brushes, and have nuts W screwed on their outer 20 threaded ends; and it will be seen that by forming the radial arms with the longitudinal slots S, through which the headed bolts T T of the longitudinal brushes pass, the said longitudinal brushes can be adjusted on the 25 radial arms in or out from the shaft itself, to bring the outer ends of the bristles of the brush into closer proximity to or farther away from the inner surface of the wire covering or screen of the sieve, when the brushes are secured 30 firmly in their adjusted position by tightening the nuts W, as will be readily understood.

In operation the spindle or shaft with its longitudinal brushes is placed in position, first, in the coarser sieve D, by placing the straight 35 end of the brush-shaft in the recess or bearing L in the inner side of one end of the sieve, and then sliding the other end of the brush-handle down in the vertical bearing-slot M, in the rounded bottom of which the said end 40 of the shaft rests and revolves. The hopper is then placed and secured on the sieve, fitting tightly thereon, as previously described, and being secured thereon by the hooks J J, engaging with the eyes K K, the lower edges of 45 the end pieces of the hopper being formed with the centrally-curved recesses A, which may have a metal bushing secured in them to prevent wear; and when the hopper is placed in operative position on the sieve the lower ends 50 of the end pieces of the hopper fit down within the ends of the sieve, their lower ends fitting down upon the shoulders F' F', formed on the inner side of the upper part of the sieve ends, as before stated, and the recess A' fits over the 55 upper sides of the respective ends of the brush shaft or spindle, so that the inner sides or surface of the ends of the sieve and hopper are perfectly smooth and even, lying in the same plane, so that the longitudinal brushes U can extend 60 the full length of the sieve, so as to brush the entire space of the sieve-cloth and leave no space on which the softened isinglass and sounds can lodge without being touched by the brushes. The hopper being thus secured upon the 65 coarser sieve, with the spindle, with its brushes in position within the sieve, the isinglass or

fish-sounds is placed in the upper part of the hopper and gradually fed down through the space C between the inner lower longitudinal edges of the partition-boards B B into the 70 sieve, where the revolving longitudinal brushes break up the isinglass or fish-sounds and force it down through the perforations or apertures of the curved sieve-bottom, the sieve and hopper having previously been 75 placed on the top of a barrel or other suitable receptacle, as shown in Fig. 1 of the drawings. When the isinglass or fish-sounds have been broken up and forced through the coarser sieve, the hopper is removed from the 80 sieve, and the shaft with its brushes lifted out and adjusted in position in the finer sieve E, when the hopper can be again secured upon this finer sieve and the broken isinglass or fish-sounds passed through the finer sieve by 85 the revolving brushes. When the isinglass or fish-sounds have been beaten and softened by the revolving brushes, so as to pass through the two sieves, the finings are ready for use.

From the foregoing description, taken in 90 connection with the accompanying drawings, the construction, operation, and advantages of my invention will be readily understood. It will be seen that my improved device or apparatus is simple and strong in construction, and will therefore not break easily or get out of order; and it is exceedingly effective in its operation. It will be seen that the longitudinal brushes can be adjusted as desired or required, and that the shaft with its 95 adjustable brushes can be readily changed from one sieve to the other. Each of the sieves is of the same general size, so that the hopper fits closely on each of them, the only difference being that the wire-cloth of 100 the two sieves is of different degrees of fineness, the apertures or interstices of one sieve-cloth being much coarser than those of the other. The sieve with the shaft and brushes can of course be used, if desired, without 105 the hopper, although it is much more convenient to employ the hopper, as shown and described.

Having thus described my invention, what I claim, and desire to secure by Letters Patent 115 of the United States, is—

The combination of a sieve consisting of end pieces, the lower edges of which are rounded and the upper edges are straight and recessed longitudinally upon their inner edges 120 to form shoulders, side pieces the ends of which project beyond the end pieces, and a wire secured to the lower edges of these end and side pieces, a bearing upon each shoulder, one of the end pieces being provided with 125 a slot at the bearing on the shoulder of that piece, a shaft journaled in said bearings, the end of which projects through the slot and is formed into a crank, brushes upon the shaft, and a hopper consisting of end and side pieces, 130 inclined partitions, and a flange or rib around the lower portion of the hopper, the portion

of the hopper below the rib being adapted to fit within the top of the sieve, and the lower edges of the end pieces being provided with bearings and resting upon the shoulders of the 5 end pieces of the sieve, substantially as and for the purpose set forth.

In testimony that I claim the foregoing as

my own I have hereunto affixed my signature in presence of two witnesses.

EBEN JOHN BEGGS.
